UNITED STATES PATENT OFFICE

CHARLES L. LOW, OF FRESNO, CALIFORNIA, ASSIGNOR TO LISENBY MANUFACTURING COMPANY, OF FRESNO, CALIFORNIA, A CORPORATION

CONTINUOUS-FEED MECHANISM FOR PRINTING PRESSES

Application filed October 12, 1929. Serial No. 399,207.

This invention relates to printing presses, and particularly to a means for supporting the stack of sheets of paper to be printed, and for maintaining the top level of the stack 5 substantially in the same horizontal plane at all times, so that the topmost sheet is in the proper position to be engaged and drawn off the stack or pile by the feed nozzle or other device interposed between the pile and the 10 printing cylinder of the press.

Ordinarily the pile supporting means is in the form of a vertically movable table or elevator whose upward movement is controlled by the lowering of level of the pile. Such 15 devices for instance are shown in my copending applications for patent, Serial No. 349,637, filed March 25, 1929, and Serial No. 391,606, filed September 10, 1929. With mechanisms of this character the placing of 20 additional paper on the elevator to replenish the pile requires that the operation of the press be temporarily halted, since the elevator table must first be lowered by hand before the additional paper can be placed thereon.

25 The principal object of my present invention is to provide a pile supporting structure in which the vertically movable elevator is eliminated, and in which additional paper may be placed thereon at any time without 30 halting the operation of the press, while at the same time the topmost sheet of the pile is automatically maintained at the proper position and level to be engaged by the individual sheet feeding means.

35 I therefore term this device a continuous paper feeder, since, as above stated, the paper may be supplied or fed thereto as needed, while the operation of the press is continued. The time necessary to press a large number 40 of sheets is therefore lessened considerably over what is needed with the press mechanisms, and no readjustment or moving of any part is necessary when placing an additional supply of paper on the device.

45 A further object of the invention is to produce a simple and inexpensive device and yet one which will be exceedingly effective for the purpose for which it is designed.

These objects I accomplish by means of 50 such structure and relative arrangement of

parts as will fully appear by a perusal of the following specification and claims.

In the drawings similar characters of reference indicate corresponding parts in the several views:

55 Fig. 1 is a sectional elevation of my improved paper supporting and feed device detached from the press.

Fig. 2 is a longitudinal section of the same.

60 Fig. 3 is a fragmentary top plan view.

Fig. 4 is a fragmentary longitudinal section of the device at its forward end showing the sheet controlling feeler and parts controlled by the movement thereof.

65 Fig. 5 is a fragmentary side outline of a press showing the paper supporting device mounted thereon and connected with the operating mechanism of the press.

70 Fig. 6 is a fragmentary cross section on the line 6—6 of Fig. 5.

75 Referring now more particularly to the characters of reference on the drawings, the numeral 1 denotes the side rails or main frame of the paper supporting device which is mounted in a fixed position between the side frames 2 of the press, which is of that type shown in said above mentioned application for patent, Serial No. 391,606.

80 Turnably mounted between and supported by the rails toward their rear end is a plurality of separated rollers 3 all disposed in common horizontal alignment with each other and with a tape roller 4 disposed ahead of the same. The rollers 3 are preferably 85 all nurled or otherwise roughened on their surfaces throughout. Endless transversely spaced tapes 5 pass about the roller 4 and about a similar roller 6 disposed adjacent the forward end of the rails 90 and supported thereby; a paper supporting plate 7 extending between the tape rollers just under the upper run of the tapes.

95 The rollers 3 and 4 are all connected by a train of gears 8 so as to rotate in the same direction and at the same speed. Another rough surfaced roller 9 is disposed just ahead of the roller 6 and is connected thereto by gearing 10 so that they both turn in the same direction. A horizontal transverse 100

apron or flange 11 extends forwardly from the roller 9 tangent thereto, a vertical stop plate 12 projecting above said apron at its forward end and extending the full distance between the side rails.

6 A pile of paper sheets 13 forming the stack to be printed is adapted to be placed on the device in forwardly combed relation, or so that the forward edges of the upper sheets extend ahead of the corresponding edges of the under sheets. The stack is held in a predetermined position laterally on the device by laterally adjustable guide plates 14. These plates depend from and are supported by a transverse rod 15 disposed above the plate 7 and mounted at its ends in brackets 16 upstanding from the side rails 1. Also supported by said rod is a longitudinally extending and adjustable rod 17 from the front end of which a link 18 flexibly depends. This link on its lower end carries a roller 19 engaging the topmost sheet of paper near its rear end so as to prevent displacement of said sheet without preventing it from being drawn horizontally off the pile. Light fingers 20 project forwardly from the link and from the guide plates 14 and engage the topmost sheet near its forward edge. These fingers prevent excessive upward displacement of said edge by the air blown between the topmost sheets from the flutter pipe 21 positioned just ahead of the plate 12.

35 The combing of the paper is initially done by hand and is carried out to such an extent that all the forward edges of the sheets lie in a substantially common horizontal plane or are alined with the plate 7, the roller 9 or the lip 11, as shown in Fig. 2.

40 It will therefore be seen that if the tapes and the various rollers are driven forwardly the entire pile will be moved forward until the forward edges of the topmost sheets engage the stop plate 12. It is then of course desired that the advancing of the paper shall be halted so as not to destroy the combed arrangement of the sheet relative to each other, and such advancing is therefore actuated in connection with the operation of the press 45 and is controlled by the positioning of the topmost sheet when its forward edge engages the stop plate.

The mechanism whereby this operation is effected is constructed as follows:

55 The shaft 22 of the roller 4 projects at one end through one of the side rails and has a pinion 23 fixed thereon. This pinion meshes with a gear 24 journaled in the adjacent side frame of the press and fixed in connection with a ratchet wheel 25 disposed on the outside of the frame. This wheel is engaged by a pawl 26 mounted on an arm 27 which projects horizontally from and is turnable axially of the wheel and gear. The pawl and ratchet 60 are arranged so that depression of the outer

end of the arm causes the ratchet wheel and gear to be rotated; the pinion 23 and various rollers interconnected therewith being then turned so that their upper surfaces move forwardly, advancing the paper toward the 70 forward end of the supporting structure.

The mechanism which causes the arm to be thus depressed is, as will be evident from an inspection of Fig. 5, the same as shown for operating the elevator in my copending application for patent, Serial No. 391,606, and is constructed as follows:

A link 28 depends from the outer end of the arm 27 and is connected at its lower end to the free end of a horizontal arm 29 pivoted at its opposite end on the adjacent frame 2. A tension spring 30 between said frame and the arm 29 tends to raise the latter, its upward movement being limited by a stop 31 projecting from the frame. Projecting laterally from the arm 29 intermediate its ends is a lug 32, adapted to be engaged by a pin 33 projecting from one face of a disc 34 (see Fig. 6). A pinion 35 is fixed in connection with said disc and is engaged by a segmental gear 36. This gear is oscillated through an arc of certain length in timed relation to the movement of the bed and cylinder of the press.

Depending from a pin 37 mounted in the 95 frame 1 above the arm 29 is a rod 38 disposed in a vertical plane intermediate the ends of said arm and in a transverse plane just to one side of said arm. The lower end of this rod is adapted to engage a shoulder 39 formed on and projecting from a block 40 secured to and projecting laterally from the arm 29. A weight 4 which is mounted in connection with the rod 38 tends to turn the same on the pin 37 and move its lower end 105 away from the shoulder, which then permits the spring 30 to act to raise the arm 29 and consequently the arm 27.

The length of this rod 38 is such that when it engages the shoulder 39 the arm 29 is depressed to such an extent that the lug 32 is barely engaged by the pin 33 at the end of the oscillation or stroke of the disc 34 in one direction. Said disc also controls the movement of the paper engaging suction nozzles N in the manner particularly shown and described in said copending application, Serial No. 391,606, being connected thereto so that said nozzles overhang the topmost sheet of paper at its forward end, just as the disc reaches the above named limit of movement. This particular relationship of the parts however has no bearing on the press invention.

If the rod 38 is moved clear of the shoulder 39 the arm 29 is free to rise, and it will then be depressed by the pin 33 upon the completion of the subsequent oscillating stroke of the disc. This will cause the ratchet wheel to be rotated and the various 120

paper supporting rollers and tapes to be moved to advance the paper toward the front end of the structure. This is accomplished by the depletion of the paper on the support by the following means:

- 5 Depending from the pin 37 inwardly of the frame 2 is an arm 42 through which a horizontal rod 43 is freely slideable, said rod having a stop S on the front side of the arm 42 to engage the same. This rod at its rear end is slideable in a support 44 depending from the front of the pile supporting structure and at its forward end is flexibly connected to the lower end of an arm 45. This 10 arm depends radially from a transverse shaft 46 journaled under the side rails 1 at their forward ends. A light weight 47 is applied to this shaft and tends to turn the arm 45 forwardly.
- 15 Projecting upwardly from and secured in connection with the shaft and extending in front of the plate 12 are transversely spaced fingers 48 having rearwardly bent offset lips 48a on their upper ends adapted to project through slots 49 cut in the plate 12 and apron 20 11. These lips form feelers for engagement with the topmost sheets of the paper on the pile. The weight 47 therefore tends to move said lips rearwardly of the apron and to pull 25 the rod 43 and the stop S forwardly and away from the arm 42. When the paper is fully advanced on the support however the topmost sheet or sheets engage and push the lips forwardly against the resistance of the weight 30 35 47 until said sheets are flush with the plate 12. In this position of the lips, the stop S abuts against the arm 42 and the control rod 38 connected therewith is maintained in a 40 position to engage the shoulder 39. Therefore as long as any sheet of paper is engaged 45 with the plate 12 (which is a position necessary to enable the nozzle N to properly engage and pin up said sheet), the rod 38 is prevented from disengaging the shoulder 39, the arm 29 remains depressed so that it can 50 not be acted on by the pin 33, and the paper advancing mechanism is prevented from functioning.

As soon as the furthest advanced and topmost sheet of the combed pile is removed, however, the feeler lips are free to and will move rearwardly of the plate 12, causing the stop S to be drawn away from the arm 42. This permits the weight 41 to act to move the 55 rod 38 clear of the shoulder 39, enabling the arm 29 to be raised and causing the same to be positively depressed by the subsequent oscillation of the disc, as previously set forth. This causes the paper to be advanced and the 60 feeler lips to be pushed forward, causing the stop S to push the arm 42 rearwardly and again placing the rod 38 in a position to engage the shoulder 9 and hold the arm 29 against further movement. This cycle of 65 operations is repeated as the fully advanced

sheets are successfully drawn off the pile by the feed nozzles or other feeding means.

When it is desired to add an additional supply to the pile, the additional sheets are first combed out and are then merely inserted under the back end of the pile already in place on the supporting structure. This operation obviously does not interfere with the operation of the press nor is it necessary to halt the same, since the fully advanced and topmost sheets of the large pile are not disturbed.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A continuous paper feeder for a printing press including supporting means for a stack of paper combed so that the upper sheets of the stack are advanced relative to those below, said means including a movable member whose movement in one direction advances the stack as a unit, a depressible arm operatively connected to said member to move the same in a stack advancing means only when said arm is being depressed, means operated in conjunction with the operation of the press to intermittently depress the arm, means acting on the arm to move the same in the opposite direction, a rod pivoted at a fixed point and arranged at its free end to normally engage and hold the arm depressed, means tending to move the rod from such engagement, a finger pivoted in connection with the supporting means and projecting above the level of the topmost sheet of the stack, means tending to move said finger toward the advancing sheet whereby said sheet in its advancement will engage and move the finger in the opposite direction, and means between the finger and rod for moving the rod to and holding the same in an arm engaging position with such opposite movement of the finger.

2. A continuous paper feeder for a printing press including supporting means for a stack of paper combed so that the upper sheets of the stack are advanced relative to those below, said means including a movable member whose movement in one direction advances the stack as a unit, a depressible arm operatively connected to said member to move the same in a stack advancing means only when said arm is being depressed, means operated in conjunction with the operation of the press to intermittently depress the arm, means acting on the arm to move the same in 120 125 130

the opposite direction, a pivoted rod positioned to normally engage and hold the arm depressed, means tending to move the rod from such engagement, a finger pivoted in connection with the supporting means and projecting above the level of the topmost sheet of the stack, an arm connected to and depending from the pivot of the finger, a horizontal rod connected to the lower end of the arm, a stop on the rod, and a member mounted in connection with said first named rod to be engaged by the stop, the stop being positioned to engage said member and hold the first named rod in its arm engaging position when the finger is moved by the movement of the paper to a fully advanced position.

In testimony whereof I affix my signature.
CHARLES L. LOW.
